UNITED STATES PATENT OFFICE.

ERNEST F. MEYER, OF LAKE CHARLES, LOUISIANA, ASSIGNOR TO HERMAN H. SCHINDLER, OF SAME PLACE.

DRAW-BRIDGE ALARM.

SPECIFICATION forming part of Letters Patent No. 288,470, dated November 13, 1883.

Application filed May 23, 1883. (No model.)

To all whom it may concern:

Be it known that I, ERNEST F. MEYER, a citizen of the United States, residing at Lake Charles, in the parish of Calcasieu and State 5 of Louisiana, have invented a new and useful Draw-Bridge Alarm, of which the following is a specification, reference being had to the accompanying drawings.

This invention relates to railway-alarms, 10 such as are used in connection with draw-bridges, and are operated by the wheels of the locomotive and cars as they pass over the track. Its object is to provide an alarm possessing superior advantages in point of simplicity, 15 durability, and general efficiency.

In the drawings, Figure 1 is a plan view of 20 a portion of the bridge and draw having the track and my improved alarm mechanism. Fig. 2 is a vertical longitudinal sectional view 25 of the same. Fig. 3 is a vertical transverse sectional view, taken through the rock-shaft that operates the alarm. Fig. 4 is a vertical transverse sectional view, taken through the shaft carrying the bell-hammer. Fig. 5 is a 30 detail sectional view, taken through the adjusting portion of the shaft that sets the alarm. Fig. 6 is a detail perspective view of the bell-hammer and its latch and operating shaft. Fig. 7 is a detail perspective view of the mechanism for setting the alarm.

Referring to the drawings, A A designate 35 the longitudinal beams on which the ties B are seated, the rails C C being secured to the ties in the usual manner.

D is the draw, which may be of any suitable 40 construction, and carries the section of track E E, as shown. At some distance from the draw a transverse rock-shaft, F, is journaled, and this shaft is provided at its ends with upwardly-projecting arms G G, having its top edge, H, 45 rounded or beveled from end to end, over which the wheels of the locomotive and cars are adapted to run to depress the said arms and turn the shaft. A coiled spring, I, is secured around the shaft F, and serves to force the same up, so that its arms G G will project above the head of the rail; and the said shaft is also provided with a downwardly-projecting arm, J, by which it can be operated, as hereinafter described.

K is a longitudinal rod or shaft, that is adapted to slide in brackets L, projecting from one of the beams A A, and extends from the draw D to the arms J, grooved rollers M being journaled on one of the beams A A under the 55 said rod to support the same. This rod is preferably constructed of compressed paper to gain lightness and obviate expansion and contraction of the same by changes in temperature, and with its ends of hardened steel to render them 60 more durable. This shaft K is formed of two sections having right and left hand screw-threads N O, respectively, on their adjoining ends, these ends being united by a sleeve-nut, P, having corresponding screw-threads Q R, so 65 that this nut can be operated to lengthen and shorten the rod, as desired. Jam-nuts S S are arranged at the ends of the sleeve-nut, and a coiled spring, T, is secured on the shaft, and acts against one of the brackets L to force the 70 shaft toward the draw.

Adjoining the end of the draw is fulcrumed 75 a bell-crank lever, U, on a cross-beam, V, so that one of its arms, W, acts against the end of the rod or shaft K, and the movement of its other arm, X, is limited by a stop-block or lug, Y. When the draw is closed, a block or projection, Z, on its under side, comes against this arm X, and causes the lever U to force the rod K, by reason of its engaging arm W, from 80 the draw. This rod K then comes against the arm J and turns the rock-shaft F, so that its arms G G will be below the head of the rails, and will not be acted upon by the wheels, and the train will pass along without sounding the 85 alarm; but as soon as the draw is opened, as indicated by the arrow, Fig. 1, if only for the width of the rail, it releases its pressure upon the lever U, and the spring T forces the rod K toward the draw, thus permitting the rock-shaft to come up by action of its spring I, so 90 that it will be operated by the wheels.

A block, A², is secured to one of the beams A A, and is provided with a bumper or cushion, B², to break the shock of the arm J as the rod 95 K releases its pressure.

C² is a rock-shaft that is journaled transversely near the rock-shaft F, and is provided with a hammer, D², and with a coiled spring, E², for forcing the shaft to cause the said ham- 100

mer to strike a bell or gong, F^2 , that is arranged on a cross-beam, G^2 .

To the rear end of the hammer or arm D^2 , which is fixed on the shaft C^2 , is hinged, preferably by means of a bail, H^2 , as shown, a latch-block, I^2 , which projects from the rear end of the said hammer, and is held in position by two spring-arms, $J^2 J^2$, which are secured to the free end of the latch-block and to the shaft C^2 . This latch-block is actuated by an arm, K^2 , projecting from the shaft F , which arm depresses the block to raise the hammer whenever its operating-arms $G G$ are depressed by the wheels of the passing train. The arm K^2 will pass the block to permit the hammer to fall and strike the gong by action of the spring E^2 , when the spring I will serve to return the said arm K^2 up past the latch-block, ready to again depress the same. The block I^2 will be caused to swing back on its hinge-bail H^2 by the upward return movement of arm K^2 , to permit the latter to pass to a position above said block; but on the downward movement of said arm the block will come against the end of the hammer and remain stationary, so that its engagement by the end of the arm will serve to raise the hammer until the engagement of the arm and block is broken, when the hammer will fall against the gong and sound the alarm. A cushion or bumper, L^2 , is preferably arranged under the hammer to break its fall against the bell and to hold it up from the latter.

It will be understood that two of these alarms can be arranged at each side the draw at suitable distances apart, and can be connected and actuated by the same longitudinal sliding rod K . This improved alarm mechanism can also be used in connection with switches, when the block Z can be arranged on the switch-track.

I claim as my invention—

1. The combination of a longitudinal sliding rod, a bell-crank lever acting against one end of the same, a spring forcing the rod against the said lever, the block or projection on the bridge for operating the lever, and a transverse rock-shaft having the upwardly-projecting arms, which are adapted to be acted upon by the wheels of the passing train, and provided with an arm arranged to be engaged by the end of the sliding rod, this said rock-shaft being adapted to operate an alarm, as set forth.

2. The combination of the operating rock-shaft having the actuating-spring, the end arms adapted to be depressed by the wheels of the passing train, the downwardly-projecting arm, the hammer, and the arm for actuating the hammer of an alarm mechanism,

with a longitudinally-sliding rod arranged to engage this said downwardly-projecting arm to throw the mechanism out of operation, and means for operating this sliding rod, as set forth.

3. The combination of the bell-crank lever, the longitudinal beams on which the track is built having the brackets, the longitudinal rod sliding in these brackets, and acted upon by one end of the bell-crank lever, the spring arranged on the rod and abutting against one of the brackets, and a transverse rock-shaft carrying arms by which it can be depressed, and provided with an arm against which the end of the sliding rod operates, the said rock-shaft being adapted to operate an alarm as it is depressed, as set forth.

4. The combination of a transverse rock-shaft adapted to be actuated by the wheels of the passing train, and provided with a projecting arm, another transverse rock-shaft carrying a bell-hammer, at the end of which hammer is arranged a spring-actuated latch that is hinged on the rear end of the hammer, and is engaged by the projecting arm on its downward movement to raise the hammer, and is thrown over on its hinges by the upward movement of the arm to permit the passage of the same, substantially as and for the purpose set forth.

5. The combination of the transverse operating rock-shaft having the end arms that are acted upon by the wheels of the passing train, and provided with the projecting alarm-operating arm, the spring for actuating this shaft, the transverse rock-shaft carrying the bell-hammer, the spring for actuating this shaft, the latch-block hinged to the rear end of the hammer, and having the springs secured to the shaft, and the bell or gong, as set forth.

6. The combination of the bell-crank lever, the projection for operating this lever, the longitudinally-sliding rod having the actuating-spring, the spring-actuated rock-shaft having the end arms, the downwardly-projecting arm, and the alarm-operating arm, the transverse rock-shaft carrying the bell-hammer, and having the actuating-spring, the spring-actuated latch-block hinged to the rear end of the hammer, and the bell or gong, as and for the purpose set forth.

In testimony that I claim the foregoing as my own I have hereto affixed my signature in presence of two witnesses.

ERNEST FERDINAND MEYER.
